Patented May 27, 1913.

UNITED STATES PATENT OFFICE.

LOUIS JARVIS FAY, OF NOGALES, ARIZONA.

SAFETY-RAZOR.

1,063,021.

Specification of Letters Patent.

Patented May 27, 1913.

Application filed November 12, 1908. Serial No. 462,232.

To all whom it may concern:

Be it known that I, LOUIS J. FAY, a citizen of the United States, and a resident of Nogales, in the county of Santa Cruz and State of Arizona, have invented certain new and useful Improvements in Safety-Razors, of which the following is a specification.

This invention is an improvement in safety razors and consists in certain novel constructions and combinations of parts as will be hereinafter described and claimed.

In the drawing, Figures 1 and 2 are longitudinal sections of a razor embodying my invention, Fig. 1, showing the safety shield adjusted down upon the blade, and Fig. 2 showing the safety shield adjusted away from the blade. Fig. 3 is an end view of the holder. Fig. 4 is a detail perspective view 20 of a blade. Fig. 5 is a detail view of the body plate of the shield.

My razor as shown, comprises a blade holder A, a blade compressor B, a safety shield C, a spring latch D, a coil spring E and a blade F. The holder A is provided at its ends with the studs A', and at its middle with the bolt A² threaded to receive the end of the blade compressor B, which blade compressor is screwed at one end upon the bolt A² and bearing at its said end against the blade compresses the latter to the concave seat A³ of the blade holder. The blade F is preferably thickened along its middle longitudinal line to afford sufficient strength at such point for the bearing of the compressor tube, and has at its center an opening F' to fit on the bolt A² and is notched in its ends at F² to receive the studs A' on the blade holder. When the blade 40 is applied to the concave face A³ of the holder and the blade compressor is screwed down to the position shown in Figs. 1 and 2, the blade will be bent to conform to the seat A³ and will be firmly held to the holder A.

Manifestly, the razor may be used when in this form, that is to say, with the holder A, the blade fitted thereon and the blade compressor screwed on the bolt A² up against the blade and holding the same firmly to the holder. The safety shield has a body plate C¹¹, whose side edges are toothed as best shown in Fig. 5, and this body plate is carried at the end of the tube C' whose bore is recessed at C² to receive the spring E which bears between oppositely facing shoulders

C³ and B³ of respectively, the safety shield C and the blade compressor B so that the spring operates normally to press the safety shield to the position shown in Fig. 1, in which it closely overlies the blade and forms a guard for safety shaving. The shield may be drawn from the position shown in Fig. 1 out along the blade compressor tube to the position shown in Fig. 2, when it is desired to clean the razor while shaving, the position of parts shown in Fig. 2, permitting the rinsing of the shield and the removal of lather, etc., from the guards of the body plate C¹¹ without unscrewing the compressor or removing the blade. When the safety shield is drawn out to the position shown in Fig. 2, which is facilitated by the formation of a shoulder C⁴ near the outer end of the tube C' of said safety shield, it may be held in such position by the latch D consisting of a plate held at one end D' within the bore of the blade compressor and extending thence toward the outer end of said bore and having a latch projection D² operating through an opening B⁴ in the blade compressor and projecting into an annular groove C⁵ in the tube C', thus locking the tube C' to the position shown in Fig. 2, until the latch is released, to which end it is provided with a thumb projection D³ projecting through an opening B⁵ in the blade compressor so the latch can be moved to free it from engagement with the tube C' and permit the said tube to be readjusted by the spring E to the position shown in Fig. 1, when so desired.

It will be noticed that the blade is not held in place by the safety shield but by the tube compressor, also as the shield or guard is movable it may be adjusted to position to permit the cleaning of the razor without unscrewing or taking it to pieces during the shaving operation. Again, if the beard is heavy the first time over may be shaved with the shield or guard raised to the position shown in Fig. 2, and said shield be then lowered for the final or close shaving, or the razor may be used with the shield entirely removed, thus forming an ordinary or open razor.

As best shown in Fig. 4 the blade may be double edged and will be wedge shape or convex surfaced on both sides.

The blade is made heavier along its central line than at other points so that when

the pressure is applied at the center of the blade by the compression tube it will be more readily transmitted or distributed throughout the blade. Usually I thicken 5 the blade along this line to the extent of about 1/128 part of an inch more than the body of the blade.

I claim—

1. A safety razor substantially as herein 10 described comprising a blade holder having end studs and a central or intermediate bolt, a blade having a central opening receiving said bolt, a blade compressor consisting of a tube screwing at one end upon 15 the bolt and bearing at said end against the blade whereby to press the latter firmly against the holder, a latch consisting of a plate within the bore of said compressor and having an outwardly extending 20 latch projection to engage with a safety shield, a safety shield having a body plate provided at its edges with guards and a tubular portion fitted over the tubular blade compressor and having an annular internal 25 groove to receive the latch projection carried by the blade compressor, the said blade compressor and safety shield being provided with oppositely facing shoulders and a spring bearing between said shoulders 30 and fitting within the tube of the safety shield and encircling the blade compressor, substantially as and for the purposes set forth.

2. A combination safety and ordinary 35 or open razor comprising a blade holder having a threaded bolt, a blade having an opening fitting over said bolt, a blade compressor having a tube screwed at one end on 40 said bolt and bearing at such end against the blade surrounding the said bolt whereby to press the blade firmly against the blade holder and a removable safety shield movable to a position against the blade in the adjustment of the implement for use as a 45 safety razor, and removable from the implement when it is desired to use the latter as an ordinary or open razor.

3. The combination with a blade holder having a threaded bolt and a tubular blade 50 compressor screwing at one end on the bolt, and a safety shield having a body plate to coöperate with the blade holder and a tubular portion encircling and movable longitudinally along the tubular blade compressor, substantially as set forth.

4. The combination with a blade holder having a threaded bolt and a tubular blade compressor screwing at one end on the bolt, of a safety shield having a body plate to 60 coöperate with the blade holder and a tubular portion encircling and movable along the tubular blade compressor, and a spring for pressing said safety shield toward the blade holder.

65 5. The combination with a blade holder

having a threaded bolt and a tubular blade compressor screwing at one end on the bolt, a safety shield having a body plate to coöperate with the blade holder and a tubular portion encircling and movable along the 70 tubular blade compressor, a spring for pressing the safety shield toward the blade holder, and a latch for holding the safety shield against the stress of said spring.

6. The combination of a blade holder 75 having a threaded bolt and a tubular blade compressor screwing at one end on the bolt, a safety shield having a body plate to coöperate with the blade holder and a tubular portion encircling and movable along the 80 tubular blade compressor, and a latch for holding the safety shield to the blade compressor when said shield is adjusted away from the blade holder, substantially as set forth.

7. A safety razor comprising a blade 85 holder, a tubular blade compressor for pressing a blade against the holder and a safety shield separate from the blade compressor and having guard devices, said 90 safety shield being movable relatively to the blade compressor toward and from the blade holder.

8. A safety razor comprising a blade 95 holder having a threaded bolt, a blade having an opening receiving said bolt, a tubular blade compressor screwing on the bolt and bearing against the portion of the blade surrounding said bolt and a removable safety shield movable along the tube compressor, and means for holding the safety shield against the blade, substantially as set forth.

9. The combination of a blade, a blade 105 holder, a blade compressor, a shield, means for pressing the shield to a position closely adjacent to the cutting edge of the blade and a separate means for holding the shield remote from the cutting edge of the blade.

10. The combination of a blade, a blade 110 holder, a blade compressor, a shield, a spring pressing the shield against the blade, and means for holding the shield against the action of the spring whereby it may be spaced away from the blade, substantially as 115 set forth.

11. A safety razor comprising a blade, a blade holder, a blade compressor for holding the blade in curved position, said compressor having a projecting handle, a safety 120 shield having a tubular portion encircling said handle and movable therealong, means operating to press the safety shield to a position closely adjacent the cutting edge of the blade, and a latch operating between 125 the handle and tubular portion of the safety shield for holding said shield against the action of such spring whereby the shield may be held remote from its said position adjacent to the cutting edge of the blade. 130

12. A safety razor comprising a guard, a blade holder, a blade clamped between said blade holder and said guard, said blade holder having an extension forming a handle, said guard having a tubular extension disposed around said handle, means for forcing said guard toward said holder, means for guiding said guard on said blade holder, and means for holding said guard in a withdrawn position from said blade holder.
